Primary Examiner — Kevin Rudzinski*Assistant Examiner* — Kathleen Jones(74) Attorney, Agent, or Firm — Buchanan Ingersoll & Rooney PC(57) CLAIM

The ornamental design for a display screen with graphic user interface, as shown and described.

DESCRIPTION

The sole FIGURE is a front view of a display screen with graphic user interface showing my new design.

The broken line showing of the display screen illustrates environment and forms no part of the claimed design.

1 Claim, 1 Drawing Sheet(56)
